US00D932186S

(12) **United States Design Patent** (10) Patent No.: **US D932,186 S**
Brunner et al. (45) Date of Patent: ** Oct. 5, 2021

(54) **TOOL BOX**

(71) Applicants: **Keter Plastic Ltd.**, Herzliya (IL);
Milwaukee Electric Tool Corporation,
Brookfield, WI (US)

(72) Inventors: **Yaron Brunner**, Kibbutz Gvat (IL);
Omer Menashri, Kibbutz Afikim (IL);
Izhar Shani, Kibbutz Gvat (IL); **Uri Parizer**, Kibbutz Hukok (IL); **Grant T. Squiers**, Cudahy, WI (US)

(73) Assignees: **KETER PLASTIC LTD.**, Herzliya (IL); **MILWAUKEE ELECTRIC TOOL CORPORATION**, Brookfield, WI (US)

(**) Term: **15 Years**

(21) Appl. No.: **29/703,816**

(22) Filed: **Aug. 29, 2019**

Related U.S. Application Data

(62) Division of application No. 29/613,377, filed on Aug. 9, 2017.

CLAIM

The ornamental design for a tool box, as shown and described.

DESCRIPTION

FIG. 1 is a top perspective view showing our new design for a tool box, with the handle at a folded position;

FIG. 2 is a front perspective view of the tool box of FIG. 1, with the handle at a folded position;

FIG. 3 is a rear perspective view of the tool box of FIG. 1, with the handle at a folded position;

FIG. 4 is a left side perspective view of the tool box of FIG. 1, with the handle at a folded position, the right side perspective view being a mirror image thereof;

FIG. 5 is a top perspective view of the tool box of FIG. 1, with the handle at a folded position;

FIG. 6 is a bottom perspective view of the tool box of FIG. 1;

FIG. 7 is a front perspective view of the tool box of FIG. 1, with the handle at an extended position; and,

FIG. 8 is a right side perspective view of the tool box of FIG. 1, with the handle at an extended position, the left side perspective view being a mirror image thereof.
